UNITED STATES PATENT OFFICE.

LEON H. WHEELER, OF ELLENSBURG, WASHINGTON; C. E. WHEELER, ADMINISTRATOR OF SAID LEON H. WHEELER, DECEASED, ASSIGNOR, BY DIRECT AND MESNE ASSIGNMENTS, OF ONE-THIRD TO RAY MCCOY, OF NEW YORK, N. Y., AND ONE-THIRD TO JOSEPH F. O'BRIEN, OF WEST NEW YORK, NEW JERSEY.

FOOT-PUMP.

1,382,603.

Specification of Letters Patent. Patented June 21, 1921.

Application filed July 30, 1917. Serial No. 183,414.

To all whom it may concern:

Be it known that I, LEON H. WHEELER, a citizen of the United States, and a resident of the city of Ellensburg, county of Kittitas, State of Washington, have invented certain new and useful Improvements in Foot-Pumps, of which the following is a specification.

This invention relates to improvements in 10 foot pumps.

In foot pumps it is desirable to have a toggle-lever device which is as light, small and compact as is possible consistently with rigidity, durability, efficiency and ease of 15 operation and it is also desirable to have the toggle-levers through which the application of power is applied to the piston to approach as close to the ground as possible; and with these ends in view I have eliminated the duplicate or twin lever parts heretofore usually 20 employed, consolidating such twin parts into one and producing a foot pump of relatively few strong, rigid and durable parts, in which the vertical power-producing 25 movement of the foot is centrally and without cramping communicated to the piston by a vertically-movable treadle lever and a link lever which forms a toggle joint therewith, and these levers with the piston to which 30 they are attached will have a maximum of air-pumping movement with a given raising of the foot-treadle and will cause a maximum effective stroke of the piston with a given size of levers.

In the preferred embodiment shown I accomplish these results by providing a pump barrel which has a centrally-located longitudinal slot and means such as suitable feet at opposite ends of the barrel for supporting 35 the same in a horizontal position, a trunk piston closely fitting within said barrel; rigid centrally-disposed toggle lever mechanism comprising a single centrally-disposed treadle lever pivotally connected to said piston within the barrel by means of integral bearing flanges and an axle or pivot member inclosed within said barrel, said treadle lever being preferably movable within the 40 barrel and through said centrally-disposed slot, a centrally-disposed link lever also moving vertically within the barrel and through said slot and forming a toggle joint with said treadle lever, said link being piv-

oted at the rear of the barrel, preferably at a point below the horizontal plane in which 55 the treadle lever is pivoted so as to allow the toggle joint to come well down within the barrel without causing a locking of such levers, and springs disposed on opposite sides of said centrally-disposed levers for 60 raising the same, the arrangement of the said slot, levers and pivots being such that the levers enter the barrel to act directly on the piston, the pivotal connection between 65 the levers is permitted to closely approach horizontal alignment with the pivotal connections at the ends of such levers and the toggle joint, without locking, is caused in its downward movement to come well down within the barrel so that the effective movement 70 of the levers is materially increased and the piston stroke is proportionately lengthened.

In the accompanying drawings, in which 75 similar reference characters designate corresponding parts throughout the several views

Figure 1 is a longitudinal section of a pump embodying my invention, with the lever parts in raised position;

Fig. 2 is a side elevation of the device with the levers lowered and locked in position;

Fig. 3 is a plan view of said device;

Fig. 4 is a longitudinal section on the line 4-4 of Fig. 2; and

Fig. 5 is a rear end elevation of the device in locked position.

Referring now to these drawings, 1 indicates a cylindrical barrel of a foot pump which is suitably supported in a horizontal 90 position by feet 2, 2^a at its opposite ends, which feet may be as shown formed integral with cylinder heads 3, 3^a respectively.

The cylinder head 3 is provided with the usual outlet valve 4 controlled by ball 4^a to 95 permit the passage of air in an outward direction only from the barrel 1 through the elbow 4^b and hose 5 to the automobile tire or the like, the said hose 5 being provided with a coupling or connection 5^a for that 100 purpose.

A trunk piston comprising a cylindrical body and having a head 6^a is adapted to reciprocate or slide within the barrel 1. To the head 6^a is secured by a screw 6^b and washer 6^c a cup-leather 6^d, the marginal

flange portion 6^a of which fits closely against the inner surface of the barrel but which is spaced from the marginal edge of the washer 6^c so that upon movement of the piston 5 ton in a forward direction air will be ejected, but when the valve 4 is closed and the piston is moved rearwardly air will be admitted in front of the piston head between the marginal flange and barrel.

10 Thus far, the device is old and well known and it is in combination with these old and well-known elements of novel means for reciprocating the piston and procuring the results above indicated that my invention resides, which novel means I shall now describe.

The barrel 1 is as shown provided in its upper surface with a slot 8 which extends longitudinally of the barrel and vertically 20 through the rear head 3^a. As illustrated, said slot is widened at its middle portion and reduced at its opposite ends.

In the construction illustrated, the disposition of this slot 8 at the top of the barrel 25 permits the entrance of a single centrally-disposed treadle-lever 7 within the barrel and allows its central or axial connection with the piston 6. As shown, the piston is provided with rearwardly-extending bearing 30 flanges 6^c in which is mounted a pivot pin 9 and the end of the treadle lever is pivoted at the middle of said pin 9 and extends upwardly and through the slot and is provided at its outer end with a foot-piece 7^a. Another single centrally disposed link lever 10 is pivoted at its rear end to a fixed part of the pump and, as shown, is so pivoted on a pin 10^a. Said lever-pin, as shown, is mounted in the foot-piece 2^a which 40 as illustrated comprises an integral extension of the rear end of the cylinder-head 3^a. The link lever 10 is as shown bifurcated and connected to the treadle by the pivot pin 10^b, the central portion of the slot 8 being 45 widened to permit the entrance within the barrel of said bifurcated toggle connection.

50 Springs 12, 12^a are stretched on opposite sides of said toggle levers 7 and 10 between the pivots 9 and 10^a for the purpose of normally pulling the piston rearwardly and raising the levers.

Suitable means, such as the latch 13, may, if desired, be provided to retain the levers in lowered position so as to enable ready 55 handling and storing of the device when not in use.

Having described my invention, I claim:

60 1. A foot pump embodying in combination a pump-barrel having air-egress means; means for supporting said barrel in a horizontal position; a piston reciprocable within said barrel; toggle-lever mechanism adapted to extend within the barrel for moving the piston in one direction, said pump being 65 provided with means for permitting the said

toggle joint to be moved to a position below the top of the barrel whereby additional effective movement of said levers will be provided and spring means for moving the piston in the opposite direction.

70 2. A foot pump embodying in combination a pump-barrel having a single centrally-disposed longitudinal slot and provided with air-egress means; means for supporting said barrel in a horizontal position 75 with said slot at its top portion; a piston fitting within said barrel; two operating levers arranged to form a toggle joint for moving the piston in one direction, one of said levers having a connection within the 80 barrel with said piston and the other lever pivotally connected at a fixed point, both levers and said joint being movable vertically through the said slot and the rear end of the barrel to a position below the top of said barrel whereby an additional effective movement of said levers and joint toward the axis of said barrel is provided; a foot-piece associated with one of said levers and spring means for moving the piston in the 85 opposite direction.

90 3. A foot pump embodying in combination a pump-barrel having a single centrally-disposed longitudinal slot and provided with air-egress means, means for supporting said barrel in a horizontal position with said slot at its top portion; a piston reciprocable within said barrel; two operating levers arranged to form a toggle joint for moving the piston in one direction, one 95 of said levers having an axial pivotal connection with said piston within said barrel and the other lever pivoted at a fixed point below the pivotal connection of the first- 100 mentioned lever, both levers and said joint being movable vertically through said slot and the rear end of the barrel to a position contiguous to the axis of said barrel whereby an additional effective movement of said 105 levers and joint toward the axis of the barrel is provided and locking of said levers in such movement is prevented, a foot piece 110 associated with one of said levers and spring means for moving the piston in the opposite direction.

115 4. A foot pump embodying in combination a cylindrical pump barrel arranged to be supported in a horizontal position and having air egress means, a piston reciprocable within said barrel, a pivot member connected with said piston and entirely enclosed within said cylindrical pump barrel, centrally-disposed toggle-lever mechanism pivotally connected at one end to said pivot member and at the opposite end to a fixed 120 part of the pump and spring means to impart return movement to the toggle lever mechanism and piston.

125 5. A foot pump embodying in combination a cylindrical pump barrel arranged to 130

- be supported in a horizontal position and having air egress means, a piston reciprocable within said barrel, a pivot member carried by said piston and entirely inclosed 5 within said cylindrical pump barrel; centrally-disposed toggle-lever mechanism comprising two levers pivotally connected together, one of which has a pivotal connection with said piston pivot member at the 10 axis of said piston and the other of which has a centrally-located pivotal connection with a fixed part of the pump and spring means to impart return movement to the toggle-lever mechanism and piston.
- 15 6. A foot pump embodying in combination a cylindrical pump barrel arranged to be supported in a horizontal position and having air egress means, a piston reciprocable within said barrel, a pivot member
- connected with said piston and entirely inclosed within said cylindrical pump barrel, another pivot member arranged at the rear of the pump in relatively fixed position and a single pair of toggle levers pivoted at opposite ends to the said pivot members and 25 also pivoted to each other intermediate the end of one of such levers, a foot piece associated with one of such levers and a spring to impart return movement to the toggle lever mechanism and piston.
- 30 In witness whereof, I hereunto subscribe my name, as attested by the two subscribing witnesses.

LEON H. WHEELER.
